UNITED STATES PATENT OFFICE

W. R. GREENLEAF, OF SILVER CREEK, NEW YORK.

IMPROVEMENT IN ROTATING VALVES FOR STEAM-ENGINES.

Specification forming part of Letters Patent No. 41,639, dated February 23, 1864.

To all whom it may concern:

Be it known that I, W. R. GREENLEAF, of Silver Creek, county of Chautauqua, State of New York, have invented new and useful Improvements in Valve-Chests and Valves for Steam Engines; and I do hereby declare that the following is a full, clear, and exact description thereof, reference being had to the accompanying drawings, making a part of this specification, in which—

Figure 1 is a horizontal section through the improved steam chest and valves arranged for a horizontal engine. Fig. 2 is a vertical section taken longitudinally through the same. Fig. 3, Sheet 2, is a side elevation showing the connecting-rod, arms, and adjusting-rod for adjusting the valves. Fig. 4, Sheet 2, is a top view of the adjusting devices of Fig. 3. Fig. 5 is an end view of one of the oscillating valves. Fig. 6 is a side view of the same. Fig. 7 is a view of the surface of one of the valves, seen as if unrolled or spread out on a plane.

Similar letters of reference indicate corresponding parts in the several figures.

This invention has for its object the construction of a steam-chest and the valves thereof in such manner that the steam entering at one side of the steam-chest will be alternately admitted through one end of each valve into the steam-cylinder and alternately allowed to escape through the opposite ends of said valves, into the exhaust-chamber, as the valves are oscillated.

It also has for its object so constructing the steam-chambers that the valves and their surrounding walls will be caused to expand equally and prevented from becoming tight in consequence of unequal exposure to the steam.

It finally has for its object a mode of adjusting all the valves simultaneously, whether the engine be running or at rest, all as will be hereinafter described.

To enable others skilled in the art to make and use my invention, I will proceed to describe its construction and operation.

In the accompanying drawings, A represents the outer casing of the steam-chest, and B B' represent two hollow shells, which are constructed with circular steam-induction passages a a a b b b, all of which communicate with their respective ports C C', and also with the central converging circular valve-chambers, as shown in Figs. 1 and 2. The induction

port D admits steam into the chamber D', which partially surrounds the valve-shells B B', and the steam, after escaping from the valves, enters the chamber E and escapes through the eduction or exhaust orifice E', as indicated by the course of the red arrows in Fig. 1.

F F' are circular conical valves, each having three, or more or less, tap ring steamways or ports, c c c, equidistant around its periphery, the ends of said steamways being open toward the steam-chamber D', and the opposite ends closed, as seen at d d, Fig. 1. These valves have, also, each three or more or less, exhaust or eduction ports or ways e e e, which open at the end toward the chamber E and are closed, at the opposite end.

In Figs. 5, 6, and 7, I have shown the form and construction of the oscillating valves more clearly. It will be seen by these figures that the valves are circular, transversely, and tapering from one end (induction end) toward the other, and that longitudinal converging slots or steam-passages are made in its circumference. These passages are made at regular intervals apart, and receive the steam at one end of the valve and discharge it at the other end, in the manner above described.

The valves being made tapering from their induction ends to their exhaust ends, they are fitted steam-tight within chambers of a corresponding shape, so that by their oscillation in said chambers they will alternately form communications with the cylinder and induction-chamber D', and with the cylinder and eduction-chamber E, the live steam entering at one end of each valve, passing down into the cylinder, and the exhaust-steam escaping at the opposite end of the valve.

G G' are set-screws, which are tapped through the ends of their respective spindle-boxes I I', so as to abut against the ends of the valve-spindles or stems, J J'. These set-screws are formed with nut enlargements h h' on them, outside of which the screw is continued for a short distance for the purpose of receiving the crank-arms i i', which are confined in place by means of the pinch-nuts j j, as shown in Figs. 1, 3, and 4. The lower ends of the short crank-arms i i' are connected together by a rod, k, which causes both arms, and, consequently, both valves to move together.

To the arm i' a slotted adjusting-rod L is pivoted, the opposite end of which is secured to the circular box-head I by means of a thumb-nut, n , which is tapped on a screw that passes through an oblong slot made through the rod L , as shown in Fig. 3. By loosening this thumb-nut the rod L can be moved endwise and the valves adjusted to their tapering seats simultaneously.

Any greater number of valves may all be adjusted at once, and retained in their adjusted position by this arrangement or mode of connecting them together.

The valve-rods $J J'$ project through stuffing-boxes $N N'$, on one side of the steam-chest, and receive crank-arms and a connecting-rod, one of the former of which receives the end of the eccentric driving-rod. I have not represented these parts in the drawings for the reason that they form no part of my invention, and that the common connections with the main shaft of the engine may be made for giving the valves an oscillating motion.

This invention may be applied to cylindrical valves as well as to those having the shape of the frustum of a cone, and the invention may also be used, by a slight change of the parts, for either distribution, cut-off, throttles, or governors, or for any other purpose for which a steam-valve is required.

Some of the advantages of this valve are: First, it can be made solid and be supported on a shaft, and is relieved of the difficulty which has been fatal to other nearly-balanced valves—viz., in equality of expansion; second, being as perfectly balanced as practicable, it is almost frictionless; third, for the same rea-

son it will not wear itself out of face or become leaky by use; fourth, having three or more steam-ways or ports opening simultaneously, any desired area of opening can be obtained, and as early in the stroke as desired, with a simple eccentric movement; fifth, the steam and exhaust ways, each being alternately open at one end and closed at the other, the contrivance is adapted to both induction and eduction in one valve.

Having thus described my invention, what I claim as new, and desire to secure by Letters Patent, is—

1. Constructing an oscillating valve, with induction and eduction passages, so arranged around its periphery that the steam will enter at one end and exhaust at the opposite end of each valve, substantially as described.

2. A tapering or conical valve having induction and eduction passages arranged around its periphery, which are alternately opened at opposite ends of the valve, substantially as described.

3. The combination of end-receiving and end-discharging valves, with their shells $B B'$, constructed with circular induction and eduction passages $a a a b b b$, substantially as any for the purposes described.

4. The arrangement, consisting of the valves $F F'$, screws $G G$, arms $i i$, connecting-rod k , and handle or lever L , substantially as and for the purpose set forth.

W. R. GREENLEAF.
